UNITED STATES PATENT OFFICE.

WILLIAM NORRIS, OF BLACKPOOL, AND HENRY SPURRIER, OF ST. ANNES-ON-THE-SEA, ENGLAND.

STEAM-GENERATOR.

SPECIFICATION forming part of Letters Patent No. 708,066, dated September 2, 1902.

Application filed February 25, 1902. Serial No. 95,552. (No model.)

To all whom it may concern:

Be it known that we, WILLIAM NORRIS, residing at Blackpool, and HENRY SPURRIER, residing at St. Annes-on-the-Sea, in the county 5 of Lancaster, England, subjects of the King of Great Britain, have invented new and useful Improvements in Steam-Generators, of which the following is a specification.

This invention relates to vertical fire-tube steam-generators, and has been designed with the objects of improving the efficiency of such generators and of rendering them more suitable for use in connection with road-vehicles propelled by steam-motors.

15 In carrying out our invention we construct these generators with fire-box crown-plates having angles which project beyond the boiler-shell and afford means whereby the boiler may be supported and so, also, that it forms 20 the bottom of the steam and water space.

In place of the water-pocket, which is cast in the iron ring surrounding the upper part of the fire-space, we cast therein external recesses for the reception of mud-cock elbows.

25 We will more fully describe our improvements with reference to the accompanying drawings, in which—

Figure 1 represents a vertical section, and Fig. 2 a plan, of a boiler in which our improvements are embodied.

30 In the drawings, *a* indicates the fire-grate, *b* a cast-iron ring surrounding the fire-space, and *d* a superheating pipe-coil embedded in the ring. This ring instead of being constructed as at present is made with a plurality of recesses *d* for the reception of the mud-cock elbows *f*.

The parts constituting the fire-box are connected with the steam and water space *g* by 40 the bolts *h*. The fire-box crown-plate *i*, as shown by the drawings, is square in plan, as this is the more economical form; but it may be triangular, pentagonal, hexagonal, or octagonal. Its angles *e* project beyond the shell 45 of the boiler and constitute means for its support on a suitable frame or bearers, such as the framework of a vehicle. It is shown to be made concave below and forms the whole of the bottom of the steam and water space

g. The outer shell *k* is riveted or secured by 50 customary means to the fire-box crown-plate and to the boiler crown-plate *l*, respectively. In the center of the steam and water space is the vertical tube *m*, through which fuel is supplied to the furnace. The crown-plate 55 *i* and top plate *l* are connected steam-tight with the tube, as indicated. The smoke-box is not shown by the drawings, but is of the usual construction, and the tube *m* passes through it. This tube is capped when the 60 boiler is not being fired. The whole of the water-space is traversed by a plurality of vertical tubes in the customary manner and are connected with the crown-plate and top plate, respectively, by known means commonly employed; but in the drawings all but a few are omitted for the sake of clearness.

What we claim as our invention, and desire to secure by Letters Patent, is—

1. In steam-generators of the class described, a crown-plate having parts extending beyond the extreme diameter of the fire-box and forming a means of support for the boiler, in combination with means for suspending the fire-box therefrom, substantially 75 as set forth.

2. In steam-generators of the class described, a cast-iron ring surrounding the upper part of the fire-space and having recesses formed in the outer part of its upper edge for 80 the reception of mud-cock elbows, substantially as set forth.

3. In steam-generators of the class described, the combination with a fire-box crown-plate, of angular extensions integral with the 85 plate, a cast-iron ring suspended from the crown-plate, recesses cast in the upper outer part of the ring, and mud-cock elbows contained within the said recesses, substantially as set forth.

90 In testimony whereof we have signed our names hereto in the presence of two subscribing witnesses.

WILLIAM NORRIS.
HENRY SPURRIER.
